WICK HOLDER LOADING MACHINE

Ernest F. Pinney, Glen Cove, N. Y., assignor to
Socony-Vacuum Oil Company, Incorporated,
New York, N. Y., a corporation of New York

Application September 1, 1948, Serial No. 47,300

1 Claim. (Cl. 18—27)

1

This invention relates to the art of candle manufacture, and is more particularly concerned with a machine for loading wick holders with wicks.

As is well known to those familiar with the art, most of the operations involved in candle manufacture have been performed slowly and laboriously by hand. For example, in the manufacture of candles by dipping wicks in molten wax, a given length of wick, depending on the desired length of the finished candle, is alternately dipped into and withdrawn from a bath of molten wax. Obviously, this operation can be, and has been, applied simultaneously to a number of wicks. For this purpose, a device, known as a wick holder, has been employed. Wick holders have consisted of wood or metal rods having a plurality of regularly-spaced slots along one edge. In practice, the wick holders have been loaded by a series of steps. These steps have included manually measuring a desired length of wick, tying a knot in one end of the wick, and individually placing each wick in a slot of the wick holder, the slipping of the wick through the slot being avoided by the knot. Manifestly, this series of steps has been disadvantageous from the standpoint of the time and the labor involved.

In a copending application, Serial Number 47,299 filed September 1, 1948, there has been described a wick holder which can engage and hold a plurality of wicks and which can be loaded in one simple operation. This wick holder can be loaded mechanically or manually.

Broadly stated, the present invention provides a method and a machine for loading wick holders, which comprises a conveyor for the wick holders of the type described in the aforementioned copending application, means for actuating the wick holders to engage and hold the wicks, and means to measure the lengths of the wicks.

Accordingly, it is an object of the present invention to provide a machine for loading wick holders. A further object is to provide a machine adapted to measure the length of a plurality of wicks and load them into wick holders, in a simple and continuous operation. An important object of the present invention is to afford a method for loading wick holders with wicks of desired length.

Other objects and advantages of the present invention will become obvious to those skilled in the art from the following detailed description taken in conjunction with the following drawings in which the preferred embodiment of the present invention is shown. It is to be clearly understood, however, that the present invention is not to be limited to the precise construction and arrangement shown. Modifications are contemplated and such must be considered to be included within the scope of this invention.

2

In the drawings:

Figure 1 is an isometric view of the complete wick holder loading machine;

Figure 2 is a vertical sectional view of a portion of the wick holder loading machine taken along the line 1—1 of Figure 1;

Figure 3 is a vertical view of the same portion of the wick holder loading machine shown in section in Figure 2, taken along the line 2—2 of Figure 1;

Figure 4 is a sectional view of a portion of the wick holder loading machine taken along the line 3—3 of Figure 3.

Preferably, and as shown in Figure 1, the wick holder loading machine comprises a frame 1 which may be fabricated from angles, I-beams, tubes, rods, or bars. The frame 1 houses a conveyor system adapted to carry wick holders from the wick holder loading end of the machine to the wick loading end of the machine. The conveyor system may include a continuous belt, or, suitably, a pair of parallel, continuous belts or chains 2. The distance between the pair of parallel, continuous chains 2 is such that each chain supports an extremity of a wick holder 3. The chains 2 are guided by a plurality of sprockets 4, or pulleys, in the case of belts, rotating freely about shafts which are attached to the frame 1.

In order to move the chains 2 in the same direction and at the same velocity, the chains 2 are actuated by a pair of sprockets 5, or pulleys, in the case of belts, rigidly mounted on a common shaft 6 rotatably attached to the frame 1, which is rotated by a sprocket or pulley 7 actuated by a prime mover.

For the purpose of ensuring the motion of the wick holders 3 from the wick holder loading end of the machine toward the wick loading end of the machine, the chains 2 are provided with a plurality of pins 8, a pair of these pins 8, one on each chain, being adapted to engage the wick holders 3. The pins 8 are juxtaposed in pairs, one on each chain, on the chains 2, so that a plane including a wick-loading edge 9 of a wick holder 3 is substantially parallel to the plane corresponding to the wick loading end of the machine. The distance between two pins 8 on each chain corresponds to the desired length of the wick.

The wick material is contained in spools or reels 10 suitably mounted above, or on top of the frame 1. The wick material is passed through a plurality of openings 11 in a bar 12, the magnitude of the openings 11 being just large enough to admit the passage of the wick material, and thence over a series of guides, suitably, a roller 13 having a plurality of grooves 14, one for each wick, located at the wick-loading end of the machine. The bar 12 having the openings 11 is

positioned below the level of the roller 13, so that the openings 11 cooperate with the grooves 14 to create a drag on the wick material as it is pulled by the wick holders.

As set forth in the copending application referred to hereinbefore, the wick holder 3 is provided with a plurality of wick-engaging slots 15 along the wick-loading edge 9 thereof. The surface of these slots cooperate with the surfaces of the slots in an internal member of the wick holder to hold the wicks in the slots. Normally, the wick holder is in the wick-holding position. This internal member is actuated out of the wick-holding position by the application of a force onto a pin 16, located at one end of the wick holder 3.

In order for the slots 15 along the wick-loading edge 9 of the wick holder 3 to engage the wick material, the wick holder 3 is carried by the chains 2 past a needle-bar cam 17 shown in detail in Figure 4. Referring now more particularly to Figures 2 and 3, the needle-bar cam 17 is rigidly mounted on the frame 1 at the wick-loading end of the machine and is adapted to engage and exert a force against the pin 16 of the wick holder 3, whereby during the latter stages of the motion of the wick holder 3 toward the wick-loading end of the machine, the internal member of the wick holder 3 is momentarily actuated out of wick-holding position. The needle-bar cam 17 may be replaced, suitably, with a fixed cam, semicircular or elliptical in shape, or it may be an eccentric cam actuated by the shaft 6 and synchronized with the speed of the chains 2. At this point, the slots 15 along the wick-loading edge 9 of the wick holder 3 engage the wick material. Continued motion of the wick holder 3 toward the wick-loading end of the machine will cause the wick-holder 3 to travel past the needle-bar cam 17, thereby releasing the pin 16 with the consequent return of the internal member of the wick holder 3 to its normal wick-holding position to hold the wick material in the slots 15.

During the cam-engaging operation just described, in order to prevent the wick holder 3 from moving out of lateral alignment and, more particularly, in order to maintain the wick holder 3 in position against the end-thrust created by the force exerted by the cam 17 against the pin 16, there are attached to the frame 1, side guide strips 18, located just outside and at right angles to the plane of the chain 2 so that they engage the extremities of the wick holder 3. The guide strips 18 may be replaced in toto, or partially, with free-rotating rollers, if desired.

After the wick-holder 3 has engaged and held the wick material, it is carried downwardly by the action of the pins 8 on the chains 2 against the drag of the wick material. The wick holder 3 is maintained in a substantially horizontal position by the upward force exerted by the drag on the wick material, and it is guided in its downward course by the chains 2 cooperating with a pair of front guides 19 and the side guides 18.

In practice, the operation of the wick holder loading machine is as follows: With the chains 2 in motion, a wick holder 3 is placed, manually or mechanically, across the chains 2 in contact with a pair of pins 8, at the wick holder loading end of the machine. As each wick holder 3 passes the needle-bar cam 17, force is momentarily exerted against the pin 16 on the wick holder 3, whereby the internal member of the

wick holder 3 is momentarily moved out of wick-holding position, and the slots 15 in the wick holder 3 engage the wick material. The latter will be held under slight tension by the pull of the preceding wick holder against the drag on the wick material. After the wick holder 3 has traveled past the needle-bar cam 17, the wick material will be held in the slots 15 of the wick holder 3. The wick holder 3 is then carried downwardly by the chains 2. At the beginning of its downward course, the wick material is cut, manually or mechanically, near the top edge of the preceding wick holder 3, thereby obtaining the preceding wick holder 3 loaded with the desired lengths of wick and ready for use in the dipping operation. The loaded wick holder may be removed from the system manually, or it may be allowed to drop onto another conveyor system to be carried into position for dipping.

Although the present invention has been described in conjunction with preferred embodiments, it is to be understood that modifications and variations may be resorted to without departing from the spirit and scope of this invention, as those skilled in the art will readily understand. Such variations and modifications are considered to be within the purview and scope of the appended claim.

I claim:

30 A machine for continuously supplying loaded candle wick holders, which comprises multiple sources of continuous wick material; an endless conveyor for the wick holders adapted to carry said wick holders in a plane that intersects the plane determined by said wick material in a substantially horizontal line; said wick holders having a plurality of wick-engaging slots corresponding in number to said multiple sources of continuous wick material along one edge thereof adapted to engage and hold wick material, and being provided with means for opening and closing said slots; means on said endless conveyor adapted to engage said wick holders for moving said wick holders toward the plane determined by said wick material, and disposed to space said wick holders along said endless conveyor so that the distance between a pair of wick holders is substantially equal to the length of a candle, and so that during the travel of said wick holders on said endless conveyor, the wick-engaging slots will substantially coincide with said substantially horizontal line; means for maintaining the wick material under tension as it is engaged by said wick-engaging slots; and cam means to actuate the opening and closing means on said wick holders when said wick-engaging slots are substantially coinciding with said substantially horizontal line.
